UNITED STATES PATENT OFFICE

2,083,749

CLEANER ELEMENT FOR CLEANING
MACHINESRowland P. Sword, Philadelphia, Pa., assignor to
Sword-Atherton Co., Inc., Philadelphia, Pa.,
a corporation of Pennsylvania

Application May 27, 1935, Serial No. 23,634

2 Claims. (Cl. 51—195)

My invention relates to new and useful improvements in a floor cleaning element for cleaning machines and has for one of its objects to produce such an element comprising a squeegee of gum rubber impregnated with a suitable abrasive for application to a floor cleaning machine.

Another object of the present invention is to provide a cleaning element of the class mentioned having a serrated working edge.

In cleaning machines of the general class used for removing dirt or extraneous matter from floors or other surfaces it is usual to employ gritty substances with the fluid which often streaks the surface being cleaned and does not regularly attain a uniform result. It is a further object of my invention to overcome these disadvantages by including the abrasive as a part of the cleaning element whereby the necessary abradant action is achieved without the use of a loose or free abrasive material.

With these and other objects in view, this invention contemplates the application of an article of manufacture to a specific use as will be fully described and then designated in the claims.

In order that those skilled in the art to which this invention appertains, I will describe its construction in detail, referring by numerals to the accompanying drawing, in which:—

Fig. 1 is a perspective view of a rotor of a cleaning machine showing a number of cleaning elements, constituting the present invention, carried thereby.

Fig. 2 is an enlarged end view of one of the supports and the assembled cleaning elements.

Fig. 3 is a side elevation thereof.

Fig. 4 is a face view of one of the cleaning elements, per se.

Fig. 5 is a view similar to Fig. 4, of a modified form of the cleaning element.

Fig. 6 is a side elevation of a further modification.

Fig. 7 is a fragmentary bottom plan view thereof.

In carrying out my invention as herein embodied 6 represents a rotor for a cleaning machine including a plurality of radial arms 61. On top of each arm is a washer plate 7 and underneath is an inverted U-shaped or channel holder 8. In the holder is a relatively thin filler plate 81 of the same width as the interior of the holder and below said filler plate 81 is a moulding strip 82 of less width than the filler plate and located longitudinally thereof intermediate its side edges thus forming recesses between the side surfaces 55 of the moulding strip 82 and the sides of the

holder 8. The washer plate, holder, filler plate and moulding strip are fastened to the arm 61 by bolts 71 or their equivalent, passing through all of said parts.

Two cleaning elements 9 are carried by each arm of the rotor and their upper ends are inserted in the recesses formed between the moulding strip 82 and the sides of the holder 8 and secured by fastening devices 83 projected through the sides of the holder, said cleaning elements and the moulding strip. The cleaning elements are thus arranged in parallelism and extend below the holder for accomplishing a wiping action on a floor.

Each cleaning element 9 is of a form generally known as a squeegee and is composed of gum rubber impregnated with grains or particles of a gritty substance or abrasive such as volcanic ash, emery, flint, pumice or any suitable equivalent material.

The abrasive substance must be fine enough as not to score or damage the surface being cleaned yet must be sufficiently coarse to readily loosen or remove dirt or extraneous matter from such surface, leaving the cleaned surface with the minimum amount of sheen to avoid the possibility of accident by slipping. Also the quantity of abrasive material in the rubber must be adequate for the purpose intended and still leave the cleaning element flexible, however the amount of the abrasive material must not be such as to make the cleaning element brittle and therefore likely to crack or break while in use.

With a cleaning element of this character applied to a cleaning machine for use in cleaning floors or other surfaces of wood, marble, stone, artificial stone or other relatively hard material, the dirt or extraneous matter will be loosened and dislodged for removal in any suitable manner.

In actual practice it is customary to use one of the edges of the cleaning element as the working surface and this working surface may be straight as illustrated in Figs. 1 to 4, or it may have serrations 10 of any desirable configuration or contour as shown in the modification 9a illustrated in Fig. 5, but in every instance the cleaning element is movable laterally.

The cleaning element may be produced in various forms or configurations and by any of the well known processes of manufacture. For instance, such element, designated by the reference numeral 9b, may be composed of molded compound rubber containing an abrasive and including flexible fingers, as shown.

I am aware that articles composed of rubber

with an abrasive incorporated therein have been used and therefore I limit myself to the provision of such a composition for use as a floor cleaning element when applied to a floor cleaning machine.

5 Having thus fully described my invention, what I claim as new and useful is:—

1. In a device of the kind described, the combination with a rotor including a plurality of radial arms, a holder carried by each arm, a filler plate within the holder, a moulding strip in the holder beneath the filler plate and of less width than the filler plate thereby forming recesses between said moulding strip and the sides of the 10 holder, cleaning elements consisting of flat strips of abrasive rubber inserted in the recesses, and means projected through the holder, cleaning elements and moulding strip for fastening said 15 cleaning elements in place.

2. In a device of the kind described, the com- 20

bination with a rotor including a plurality of radial arms, an inverted U-shaped or channel holder on the under side of each arm, a filler plate of substantially the same width as the inside of the holder mounted within and against the top wall of said holder, a moulding strip of less width than the filler plate and placed against the latter longitudinally thereof intermediate the sides edges thus forming recesses between the moulding strip and the sides of the holder, a washer plate on top of the arm, fastening devices projected through the washer plate, arm, holder, filler plate and moulding strip for securing said parts together, cleaning elements comprising flat strips of abrasive rubber inserted in the recesses, and fastening devices projected through the sides of the holder, the cleaning elements and the moulding strip for attaching said cleaning elements.
